MUZZLE ATTACHMENT FOR GUNS

Samuel G. Green, Gray, Ga.

Application October 16, 1936, Serial No. 105,947

6 Claims. (Cl. 89—14)

(Granted under the act of March 3, 1883, as
amended April 30, 1928; 370 O. G. 757)

The invention described herein may be manufactured and used by or for the Government for governmental purposes without the payment to me of any royalty thereon.

5 This invention relates to a muzzle attachment for guns and more particularly it has reference to that class of attachments serving to check recoil, silence the report and conceal flash.

The principal object of this invention is to 10 provide an inexpensive attachment which may be readily disassembled for cleaning and replacement, and will reduce the pressure progressively so as to eliminate a blasting effect.

To these and other ends, the invention consists in the construction, arrangement and combination of elements described hereinafter and pointed out in the claims forming a part of this specification.

A practical embodiment of the invention is 20 illustrated in the accompanying drawing, wherein:

Fig. 1 is a view in side elevation of the improved muzzle attachment applied to a gun.

Fig. 2 is a longitudinal sectional view.

25 Fig. 3 is a detail view of the inner front tube.

Fig. 4 is a sectional view on the line 4—4 of Fig. 2.

The attachment is conveniently formed of two parts comprising an imperforate rear outer tube 30 securable to the muzzle of a gun barrel 6 as by a threaded engagement 7 and a front inner tube 8 inserted in the outer tube and having its rear portion in threaded engagement 9 with the outer tube and with its rear end 10 abutting a shoulder 11 of the outer tube. This connection between the inner and the outer tube is some distance forwardly of the muzzle of the gun barrel.

The inner tube has an external collar 12 in 40 front of its threaded portion and this collar engages a shoulder 13 at the front end of the threads of the outer tube. The collar serves as a guide during insertion of the inner tube and blocks off the threads to prevent them from being 45 fouled by carbon. The portion of the inner tube in front of the collar 12 is spaced from the outer tube to provide an annular chamber 14 open at its front end. When assembled the inner tube projects from the outer tube.

50 The outer tube is formed with an expansion chamber 15 flaring from a point directly in front of the barrel and terminating at the shoulder 11 where it meets the inside surface of the inner tube.

55 The inner tube has a cylindrical expansion

chamber 16 in its rear portion and a forwardly constricted chamber 17 in its front portion which terminates in a cylindrical outlet 18. The outer wall 19 of the chamber 17 is also tapered to provide a large outlet 20 for the annular chamber 14 and it terminates or merges with a baffling surface 21 which is perpendicular to the axis of the attachment and serves to deflect gases away from the outlet 18. The front edge of the outer tube is positioned intermediate the 10 length of the tapered outer wall 19.

The inner tube is provided with a plurality of rows of apertures 22 progressively increasing in size from rear to front. When the gases flow through the attachment, a portion will be vented 15 through the rear row of apertures and the pressure within the attachment will be accordingly reduced. Since the flow of gases through the apertures is governed by the pressure within the attachment and since the pressure is decreasing the next or middle row of apertures must be larger than the rear row in order to vent a larger amount of the gases. By virtue of this arrangement the reduction of the pressure within the attachment will be at a uniformly 25 increasing rate. The front row of apertures are located at the beginning of the constricted chamber 17.

The combined volume of the chambers 15, 16 and 17 is approximately equal to the volume of 30 the gun barrel including the cartridge chamber. For the purpose of consuming the unburned powder and eliminating flash, the attachment has the effect of doubling the length of the gun barrel, which relation appears to be the most 35 beneficial. I have found that when the volume of the attachment is greater than the volume of the barrel an internal flashing or blasting effect is produced which will damage the parts.

The chambers 15 and 16 permit expansion 40 of the gases and give time for burning. The constricted chamber 17 serves as a choke to further increase the burning time in the chambers 15 and 16 and to increase the velocity of the balance of the gases which issue through the 45 outlet 18. This increased velocity is obtained without back pressure and tends to choke flash.

In order to secure the beneficial results just outlined the expansion chambers 15, 16, and the chambers 17 and 18 should preferably have 50 a definite relation to one another.

The chamber 15 should be between two and three calibers in length, the chamber 16 between four and five calibers, the chamber 17 between three and one-half and four and one-half cali- 55

bers and the chamber 18 about one and one-half calibers.

The purpose in positioning the outlet of the chamber 14 in rear of the outlet 18 and in deflecting the vented gases by the baffle 21 is to prevent intermingling of the cooler gases from the chamber 14 with the gases of higher temperature and greater velocity that issue through the outlet 18. Intermingling of these gases produces reignition of the cooler gases and a resulting flash. This type of attachment is intended primarily for short burst firing where it is desired to obtain an optimum temperature from 900 to 950 degrees in a minimum of time.

16 I claim:

1. A muzzle attachment for a gun comprising an outer tube securable to an element of a gun, said tube having a conical forwardly flared wall forming a chamber, an inner tube secured to the outer tube forwardly of said chamber and spaced from the outer tube to provide an annular chamber, the inner tube having a cylindrical portion forming an expansion chamber in continuation of the flared chamber and a tapered contracted portion forming a chamber with an axial outlet, the cylindrical portion of the inner tube also having apertures increasing in size from rear to front and leading to the annular chamber.

2. A muzzle attachment for a gun comprising an outer tube securable to an element of a gun, said tube having a conical forwardly flared wall forming a chamber, an inner tube secured to the outer tube forwardly of said chamber and spaced from the outer tube to provide an annular chamber, the inner tube having a cylindrical portion forming an expansion chamber in continuation of the flared chamber and a tapered contracted portion forming a chamber with an axial outlet, the inner tube also having apertures in its cylindrical portion leading to the annular chamber.

3. A muzzle attachment for a gun comprising an outer tube securable to an element of a gun, said tube having a wall forming a flared expansion chamber in its rear portion for initially receiving gases of discharge, an inner tube secured to the outer tube and having a cylindrical portion spaced therefrom over a large portion of its length to provide an annular chamber open at its front end, said tube having a tapered contracted portion projecting from the front end of the outer tube, and the cylindrical portion of said tube having apertures leading to the annular chamber.

4. A muzzle attachment for a gun having walls forming from rear to front a flared expansion chamber, a cylindrical expansion chamber, and a tapered contraction chamber, an imperforate cylindrical sleeve over a portion of the attachment and spaced therefrom to provide an annular chamber and terminating intermediate the ends of the wall forming the tapered contracted chamber to provide a forwardly enlarging outlet and means for venting gases through the wall forming the cylindrical expansion chamber of the attachment to the annular chamber.

5. In combination, a gun barrel, an attachment on the muzzle having a wall forming from rear to front a flared expansion chamber, a cylindrical expansion chamber, a tapered contraction chamber and an outlet chamber, the volume of said chambers being substantially equal to the volume of the gun barrel, and means for venting gases through the wall forming the cylindrical expansion chamber.

6. In combination, a gun barrel, an attachment on the muzzle having a wall forming from rear to front, a flared expansion chamber two to three calibers in length, a cylindrical expansion chamber four to five calibers in length, a tapered contraction chamber three and one-half to four and one-half calibers in length, a cylindrical outlet chamber one and one-half calibers in length, and means for venting gases through the wall forming the cylindrical expansion chamber.

SAMUEL G. GREEN.
